UNITED STATES PATENT OFFICE

2,525,374

CARBURETOR ARRANGEMENT FOR V-TYPE
AIR COOLED ENGINES

Jaroslav Růžička, Prague-Smichov, Czechoslovakia, assignor to Tatra, národní podnik, Koprivnice

Application August 29, 1947, Serial No. 771,362
In Czechoslovakia January 2, 1939Section 1, Public Law 690, August 8, 1946
Patent expires January 2, 1959

2 Claims. (Cl. 123—171)

1

In air-cooled engines with the cylinders arranged in V the carburettor is usually arranged in the space provided between the cylinders, since the sucked-in air may be distributed into the cylinders in the best and shortest way possible. A drawback of this arrangement consists in that the carburettor is situated just in the path of the hot air led away from the cylinders. An arrangement, it is true, has already been proposed in the form of a hollow slide valve whereby the air is directed into the carburettor either from the cool external space or from the warm space between the cylinders or from both spaces simultaneously in a mixture of any desirable mixing ratio, but in spite of this arrangement even in this case the drawbacks occur in consequence of the carburettor being excessively heated by the hot air itself. Engines of this type are surrounded by a plate or similar jacket serving for directing the cooling air and distributing the whole space round the engine into a cold and a warm space. In the above mentioned arrangement serving for the admission of hot air to the carburettor in any desired manner the carburettor is connected to the cold space by a pipe, but in such manner, that the connection with this space can be progressively closed and at the same time the connection with the warm space can be opened, it being possible to arrange an air filter in the inlet pipe.

The arrangement according to this invention for eliminating the drawback of the necessity of arranging the carburettor in a hot space, consists in that the middle portion of the inlet hollow body is enlarged to form a housing in such manner that the whole carburettor is arranged directly in said enlarged portion in consequence of which the entire carburettor is exposed to a medium of such temperature which is most favourable for the carburettor operation.

The accompanying drawing shows diagrammatically by way of example an embodiment of the object of the present invention.

The hot space is between the cylinders 2 and 3 and is limited by a jacket 4. Through this space 1 a hollow cylindrical body 5 extends and opens on both frontal extremities into the cool space 6 a widened portion 7 being centrally arranged in the shape of a housing wherein the carburettor 8 is supported. The ends of the body 5 are provided in a well known manner with apertures which co-operate with the apertures in the jacket

2

and the inner space of the body is filled out with slides having openings and serving for closing respectively opening the admissions of cold or hot air respectively for preparing a suitable warm mixture filters 9 being preferably provided in a portion of the hollow body 5. The body 7 having the shape of a housing is provided with a cover 10 rendering possible the access to the carburettor.

10 I claim:

1. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, and a carburettor arranged in said casing and adapted to be supplied with air from said cooler space through said hollow cylindrical body.
- 15 2. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, and a carburettor arranged in said casing and adapted to be supplied with air from said cooler space through said hollow cylindrical body.
- 20 3. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, a carburettor arranged in said casing and adapted to be supplied with air from said cooler space through said hollow cylindrical body, and rotatable slide valves in the ends of said hollow cylindrical body for controlling the amount of air supplied to said carburettor.
- 25 4. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, a carburettor arranged in said casing and adapted to be supplied with air from said cooler space through said hollow cylindrical body, and rotatable slide valves in the ends of said hollow cylindrical body for controlling the amount of air supplied to said carburettor.
- 30 5. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, a carburettor arranged in said casing and adapted to be supplied with air from said cooler space through said hollow cylindrical body, and rotatable slide valves in the ends of said hollow cylindrical body for controlling the amount of air supplied to said carburettor.
- 35 6. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, a carburettor arranged in said casing and adapted to be supplied with air from said cooler space through said hollow cylindrical body, and rotatable slide valves in the ends of said hollow cylindrical body for controlling the amount of air supplied to said carburettor.
- 40 7. In an internal combustion engine having the cylinders arranged in V-formation, a jacket enclosing the cylinders and the hollow space between the same, a hollow cylindrical body extending transversely through the jacket and communicating with both its ends with the cooler space outside said jacket, a casing within said jacket and arranged centrally within the hollow space between said cylinders and communicating with the central portion of said hollow cylindrical body, a carburettor arranged in said casing and adapted to be supplied with air from said cooler space through said hollow cylindrical body, and rotatable slide valves in the ends of said hollow cylindrical body for controlling the amount of air supplied to said carburettor.
